UNITED STATES PATENT OFFICE

2,517,500

KEY CASE

Floyd O. McPherson, Ridgeway, Wis., and Carl G. Gunderson, Frost, Minn.; said Gunderson as signor to said McPherson

Application October 30, 1947, Serial No. 782,978

5 Claims. (Cl. 70—456)

1

This invention relates to new and useful improvements in key cases and more particularly this invention relates to an improvement in Patent No. 2,306,970.

The primary object of the present invention is to provide a key case including novel and improved means for retaining one or more keys in position to the case.

Another important object of the present invention is to provide a key case including novel and improved means for actuating or releasing the means for holding the keys in the case.

A further object of the present invention is to provide a key case so constructed as to present a smooth surfaced article of compact form that occupies very little space.

A still further aim of the present invention is to provide a key case that is simple and practical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is an elevational view of the present key case, with parts broken away and shown in section, and with dotted lines showing a key retained therein;

Figure 2 is a top plan view of Figure 1, and showing a plurality of keys fixedly positioned in the case;

Figure 3 is an enlarged transverse vertical sectional view taken substantially on the plane of section line 3—3 of Figure 2, and showing in dotted lines the manner in which the keys are released from the case;

Figure 4 is a perspective view of one of the spacer strips used in conjunction with the present invention;

Figure 5 is an enlarged vertical sectional view taken substantially on the plane of section line 5—5 of Figure 1 to show the manner in which the spacer strips are retained relative to the walls of the case; and,

Figure 6 is a perspective view of the key case in slightly modified form.

Referring now to the drawing in detail, wherein for the purpose of illustration, there is disclosed a preferred embodiment of the present invention, the numeral 10 represents the present key case generally, comprising a pair of spaced

parallel outer walls 12 and 14 and an intermediate wall 16, all of which are provided with enlarged, rounded rear edges 18 and forwardly converging edges 20 and 22 that terminate in a rounded forward edge 24.

The outer walls 12 and 14, and the intermediate wall 16 are retained spaced relative to each other by spacer strips 26, the lower edges 28 of which are co-planar with the edges 20 of the walls 12, 14 and 16. The forward arcuated extremities of these spacer strips are disposed adjacent the forward edges 24 and the outer edge 29 of the extremities 30 are co-planar with the edges 24 of the walls.

15 Removably connecting the rear portions of the walls, 12, 14 and 16, is a transverse pin 32 that pivotally supports a plurality of keys 34 that are placeable between the outer walls and intermediate wall.

20 Slidably mounted in a transverse recess or groove 36 in a spacer strip between walls 12 and 16, and in an aperture 38 provided in wall 12, communicating with recess 36, is a push button or rod 40, one extremity 42 of which normally projects outwardly from aperture 38 and the other extremity 44 of which abuts one end 46 of a leaf spring or resilient arm 48 that is positioned between the walls 12 and 16 and which has one end fixed in slots or openings 47 in one of said spacer strips. A vertical recess 49 is provided in the inner face of wall 16 and opposes the spring arm 48. The free end 50 of this spring arm is flared outwardly to facilitate the placement of a key between the spring arm and the inner face of wall 12 to be frictionally retained in position therebetween.

25 An annular shoulder 52 is provided about the rod 40 and limits the outward movement of the rod relative to wall 12.

30 Slidably mounted in opposed apertures 53 in the walls 12 and 16, and in grooves 54 provided in the spacer strips between the walls 12, 14 and 16, is a further transverse push rod 56, one end 58 of which normally projects outwardly from wall 12 and the other end 60 of which abuts one end 62 of a further spring arm 64 having a flared free end portion 66 that facilitates the placement of a key between the spring arm 66 and wall 16. The opposite end of said spring arm 64 is fixed in a further slot 47 provided in the spacer strip between the walls 14 and 16. A recess 68 is also provided in the inner face of wall 14 and opposes the arm 64.

35 The rod 56 is also provided with an annular rib or shoulder 70 that bears against the inner face

of wall 16 to limit the outward movement of the push rod 56 relative to the wall 12, and to correctly position the arm 64 between walls 14 and 16 so that the same will frictionally engage a key plate between the walls 14 and 16.

To release a key engaged between the spring arm and the outer wall, it is merely necessary to press the push rod inwardly, so that the spring arm will engage the recess oposing the same and the case may be inverted whereby the key will pivot outwardly therefrom.

Figure 6 illustrates the present key holder in slightly modified form, wherein the outer wall 14, push rod 58, and spring arm 64 are removed therefrom so that the same may be reduced in size and so that the same will receive a single key, although the relative distance between walls 12 and 16 may be increased so that the same may engage a plurality of keys.

It is preferred, that one face of the spacer strip 26 be provided with protuberances or projections 72 that frictionally engage suitable seats or recesses 73 provided in either the side walls 12 and 14 or the intermediate wall 16.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A key case comprising first and second side walls, an intermediate wall disposed between said side walls, spacer strips interposed between said intermediate wall and each of said side walls,

means for retaining said spacer strips relative to said side walls, first and second spring arms disposed between said intermediate wall and said first and second side walls, said spring arms including inner end portions anchored to said spacer strips, a first push rod slidably carried by said first side wall for actuating said first spring arm, and a second actuating push rod slidably carried by said intermediate wall and said first side wall for actuating said second spring arm, said first spacer strip having notches for guiding the sliding movement of said push rods.

2. The combination of claim 1 wherein said first spring arm and said first push rod are longitudinally spaced relative to said second spring arm and said second push rod.

3. The combination of claim 1 wherein said intermediate wall and said second side wall include recesses for respectively receiving said first and second spring arms when said spring arms are actuated by said push rods.

4. The combination of claim 1 wherein the free ends of said spring arms are arcuated to provide bearing surfaces.

5. The combination of claim 1 wherein said means for retaining said spacing strips relative to said side walls include longitudinally spaced protuberances carried by said spacing strips, said side walls having recesses for receiving said protuberances.

FLOYD McPHERSON.
